ATTORNEY.

UNITED STATES PATENT OFFICE.

GEORGE S. EDER, OF KANSAS CITY, MISSOURI.

PUMP.

Application filed October 13, 1921. Serial No. 507,435.

To all whom it may concern:

Be it known that I, GEORGE S. EDER, a citizen of the United States, residing at Kansas City, in the county of Jackson and 5 State of Missouri, have invented certain new and useful Improvements in Pumps, of which the following is a specification.

This invention appertains to certain improvements in pumps generally, and more 10 particularly to a type thereof adapted for use in pumping out the contents of gas and oil barrels, containers, and the like.

The principal object of the invention is 15 to provide for a pump of the class mentioned, and one of an extremely simple, durable, and efficient construction, arrangement, and operation of parts, such as is capable of being manufactured at a minimum and comparatively low cost, and which is 20 readily and easily installed in operative position, or removed therefrom, and otherwise manipulated for its intended purposes.

With the foregoing and other objects in 25 view, the invention resides in the certain novel and useful construction, arrangement and operation of the parts thereof as will be hereinafter more fully described, set forth in the appended claims, and illustrated in the accompanying drawing, in which:—

30 Figure 1 is a side elevation, partly in section, of a preferred embodiment of the pump,

Figure 2 is a horizontal section taken on the line 2—2 of Fig. 1,

35 Figure 3 is a plan view of the removable head slot or cap per se of the pump cylinder, and,

Figure 4 is a horizontal section taken on the line 4—4 of Fig. 1.

40 Referring to the drawing, the numeral 10 indicates an open ended cylinder having its lower end seated within an annulus 11 formed in a valve casting 12, and its upper end normally closed by means of a head block or cap 13 which is clamped in position, together with the cylinder 10 and the valve casting 12, by means of bolts 14 which are passed downwardly through openings formed in a flanged portion 15, of the head 45 or cap 13, and similarly formed aligning openings formed in a flanged portion 16 of the valve casting 12. Mounted within the cylinder 10 and projecting upwardly and concentrically of the head block or cap 13 50 is a piston rod 17 having its upper end por-

tion formed to provide an enlargement 18, arranged to function as a stop for limiting the downward reciprocating movement of the piston, and the extreme free end of the end portion is bifurcated to provide a pair 60 of spaced ears 19 immediately above the enlargement 18. An operating hand lever 20 is pivoted, by means of a pivot pin 21, between the ears 19 of the piston rod 17, and is further pivoted, by means of a pivot pin 65 22, between a pair of ears 23 formed at the upper end of a fulcrum bar or rod 24, which, in turn, is pivoted at its lower end on a pivot pin 25 extending between a pair of ears 26 projecting outwardly in spaced parallel relation at one side of the upper face of the head block or cap 13. Mounted on the lower end of the piston rod 17 are a pair 70 of annular clamp collars 27 and 28, between the opposed faces of which are positioned a pair of pump leathers or the like 29 and 30, which are cupped in opposite directions and correspondingly fitted over the collars 27 and 28, respectively. The inner of the collars 27 is arranged in abutting relation 75 to an enlargement 31 formed inwardly of the lower end of the piston rod 17, while the outer end face of the outer of the collars 28 is abutted against clamp nut 32 which is threaded onto the free end of the piston rod 80 17, whereby to effect the securing of the collars 27 and 28 in position for the clamping of the cupped leathers 29 and 30 therebetween.

85 The valve casting, designated generally at 90 12, comprises an enlarged inlet valve portion 33, and an angularly offset and upwardly curving outlet portion 34, the upper open side of the inlet portion 33 being formed to provide the annulus 11 for the 95 seating therein of the lower end of the pump cylinder 10, while the lower side of the same is provided with a cylindrical extension or nipple 35 having a threaded bore therein for the connection thereto of a suitable length of pump tubing 36, which bore is of a less diameter than that of the interior of the portion 33, or of the upper opening thereof. Fitted within the bore of the extension or nipple 35, immediately above 100 the inwardly threaded end of the tubing 36, is a valve seat 37 for supporting thereon a ball valve 38, the upward movement of which, during the upward or suction stroke 105 of the piston 17, is limited by means of an 110

annular guard 39 which is seated in the annulus 11 beneath the connected end of the cylinder 10, and has a cross bar 40 disposed diametrically thereof and in the path 5 of the ball valve 38 in its opening movement from the seat 37. The free end of the upwardly curved portion of the outlet portion 34 of the valve casting 12 has fitted into the bore thereof a valve seat 41 supporting in position thereon of an outlet ball valve 42, which is enclosed within a casing 43 threaded onto and exteriorly of the free end portion 34, and this casing has an outlet nipple or extension 44 which has its bore 10 threaded to receive the lower end of a vertically extending discharge pipe or tube section 45, which, in turn, has its upper end threaded to receive thereon an L-coupling 46 or the like for the connecting to 15 the same of a downwardly and forwardly curving discharge hose or spout 47.

For adapting the pump for use in drawing off the contents of barrels, containers or the like, the tubing 36 is to be inserted into 20 the usual bung hole of a barrel, (not shown), and is supported in operative position in a clamp member which is formed in two sections 48 and 49, the former provided with a lateral ear 48' and the latter with the pair of 25 spaced lateral ears 49', between which extends the ear 48. The ears 48', 49' are pivoted together as at 50, and which are to be clamped around the tubing 36 at the required 30 distance upward from the lower end thereof 35 to admit of the latter end extending into the barrel and in contact with the bottom wall thereof, the parts or sections 48 and 49 being provided with a fastening means, preferably in the form of a bolt 51 passed through a 40 pair of lateral extensions 51' formed thereon at the side of the same opposite to the point of pivotal connection thereof one with the other. The bolt 51 is disposed at right angles with respect to pivot 50. The sections 45 48 and 49 are each formed with complementary lower threaded portions 52 and complementary intermediate threaded portions 53 of a greater diameter than the lower portion 52, whereby to adapt the support for threaded 50 engagement in bung holes of different sizes, and by adjusting the clamp member vertically on the tubing, the latter may be regulated correspondingly for insertion into barrels or containers of different depths.

55 In the operation of the pump, the usual bung of a barrel, cask or the like, (not shown) is removed, and the tubing 36 inserted into the opening thereof to a proper depth to assure of the entire drawing off of the contents of the same, and is supported in position by either one or the other of the threaded portions 52, 53, being screwed into the said bung opening, the cast member being 60 adjusted vertically on the tubing for the

purpose. When it is desired to draw off the 65 contents of the barrel or container, the handle 20 is grasped in the usual manner and moved up and down for the purpose of reciprocating the piston 17, on the upward stroke of which, the ball valve 38 will be 70 lifted from its seat 37 and a portion of the contents of the barrel or container drawn into the cylinder 10, during which operation, the ball valve 42 will be held on its seat 41 by the suction created by the piston. On the 75 down stroke of the piston 17, the ball valve 38 will be forced back onto its seat 37 to close all communication between the container and the pump cylinder 10, and the 80 contents of the latter forced outward 85 through the outlet portion 34 of the valve casting 12, where it will lift the ball valve 42 from its seat 41 and pass through the casing 43 into the tube 45 and discharge from the hose or spout 47. During successive reciprocations of the piston 17, this operation will be repeated as long as desired or until the container has been completely 90 emptied of its contents. It is to be here noted that the cylinder may be accurately 95 designed for the purpose of delivering measured quantities of the liquid contents of barrels or containers, and after the manner usually employed in dispensing lubricating oils or gasoline for use in automobiles 100 and the like. It is also to be here noted that the lower end of the tubing 36 is cut away as at 54, and preferably on a line diagonally upward at one side of the same to provide a vertically elongated opening, whereby to 105 facilitate the drawing off of all of the usable contents of the barrel or container without affecting the drawing off of any dregs or sediment which may have been precipitated to the bottom thereof, when the tube 36 has 110 its lower end resting on the bottom wall of a barrel or other container and the opening is of a length to have its upper end disposed above the level of the dregs or sediment for the purpose leading outwardly and 115 downwardly from the cylinder 10, from a point above the limit of the upward stroke of the piston, is a drain pipe 55 through which any and all of the liquid, being pumped and seeping past the piston head, 120 will be returned to the barrel or other container, the lower end of the same being projected into the latter for such purpose, or otherwise arranged to discharge such overflow liquid therein, or into any other separate container as may be desired or necessary.

From the foregoing, it will be readily apparent that, while a preferred embodiment of the pump has been described and illustrated herein in specific terms and details of construction, arrangement, and operation, various changes in and modifications of the

same may be resorted to without departing from the spirit of the invention, or the scope of the claims appended hereto.

Having thus fully described the invention, 5 what is claimed, is:—

1. A pump for barrels or the like comprising a cylinder, a piston operating therein, a valved inlet and a valved outlet leading to and from said cylinder, a tube depending from said valved inlet and adapted for insertion in a bung hole of a barrel, a two part clamping element for connecting the tube with bung holes of different sizes and including an upper clamping portion and 10 intermediate and lower threaded bung hole engaging portions, and said upper portion having means at one side for pivotally connecting the parts together and further provided with means at its other side for securing the parts together in clamping position, and said intermediate portion of 15 greater diameter than said lower portion. 50
2. A pump for barrels or the like comprising a cylinder, a piston operating therein, a valved inlet and a valved outlet leading to and from said cylinder, a tube depending from said valved inlet and adapted for insertion in a bung hole of a barrel, a two part clamping element for connecting the tube with bung holes of different sizes and including an upper clamping portion and intermediate and lower threaded bung hole engaging portions, and said upper portion having means at one side for pivotally connecting the parts together and further provided with means at its other side for 20 securing the parts together in clamping position. 55
3. A pump for barrels or the like comprising a cylinder, a piston operating therein, a valved inlet and a valved outlet leading to and from said cylinder, a tube depending from said valved inlet and adapted for insertion in a bung hole of a barrel, a two part clamping element for connecting the tube with bung holes of different sizes and including an upper clamping portion and intermediate and lower threaded bung hole engaging portions, and said upper portion having means at one side for pivotally connecting the parts together and further provided with means at its other side for 25 securing the parts together in clamping position, and said intermediate portion of greater diameter than said lower portion, and said pivotally connecting means disposed at right-angles with respect to said securing means. 60
4. A pump for barrels or the like comprising a cylinder, a piston operating therein, a valved inlet and a valved outlet leading to and from said cylinder, a tube depending from said valved inlet and adapted for insertion in a bung hole of a barrel, a two part clamping element for connecting the tube with bung holes of different sizes and including an upper clamping portion and intermediate and lower threaded bung hole engaging portions, and said upper portion having means at one side for pivotally connecting the parts together and further provided with means at its other side for 30 securing the parts together in clamping position, and said intermediate portion of greater diameter than said lower portion, and said pivotally connecting means disposed at right-angles with respect to said securing means. 65
5. A pump for barrels or the like comprising a cylinder, a piston operating therein, a valved inlet and a valved outlet leading to and from said piston, a tube depending from said valved inlet and adapted for insertion into a bung hole of a barrel, and a two part clamping element for securing said tube to bung holes of different diameters and including an upper clamping portion and intermediate and lower threaded bung hole engaging portions, said parts provided with laterally extending interengaging ears pivotally connected together, and further having lateral extensions and means extending through 35 the extensions for clamping the parts in position. 70

In testimony whereof, I affix my signature hereto.

GEORGE S. EDER.
